C. F. GAISER.
OIL TREATING APPARATUS.
APPLICATION FILED NOV. 2, 1917.

Patented July 29, 1919.

Inventor,
Charles F. Gaiser
By Bakewell & Currie Atty's.

UNITED STATES PATENT OFFICE.

CHARLES F. GAISER, OF CHICAGO, ILLINOIS.

OIL-TREATING APPARATUS.

1,311,268.

Specification of Letters Patent. Patented July 29, 1919.

Application filed November 2, 1917. Serial No. 199,832.

To all whom it may concern:

Be it known that I, CHARLES F. GAISER, a citizen of the United States, residing at Chicago, Illinois, have invented a certain 5 new and useful Improvement in Oil-Treating Apparatus, of which the following is a full, clear, and exact description, such as will enable others skilled in the art to which it appertains to make and use the same.

10 This invention relates to oil stills and oil treating apparatus of the kind that comprise a coil of pipe or a number of pipes connected together in such a manner that they form a continuous conduit through which 15 the oil being heated flows, said coil or conduit being formed from ordinary metal pipe or tubing and heated by a gas flame, furnace or other suitable means.

One objectionable feature of oil stills and 20 oil treating apparatus of the kind referred to is that they do not heat the oil uniformly, especially if large-sized pipe or tubing is used to form the coil, owing to the fact that the heat will not penetrate clear through the 25 oil and raise the oil at the center of the coil to the required temperature. If an extremely high temperature is used so as to try to overcome this objection there is great danger of the oil near the outer surface of 30 the oil becoming scorched.

Still another objectionable feature of such stills and oil treating apparatus is that there is no way of ascertaining the average temperature of the oil flowing through the coil.

35 The main object of my invention is to provide an oil still or oil treating apparatus of the general type referred to, whose coil or continuous conduit is so constructed that the oil flowing through same will be heated 40 uniformly and without danger of scorching the oil.

Another object is to provide an oil still or oil treating apparatus that is equipped with a coil or continuous conduit and a 45 pressure gage combined in such a manner that the operator in charge of the apparatus can ascertain at any time the average temperature of the entire body of oil flowing through the coil.

50 To this end I have devised an oil still or oil treating apparatus equipped with a heating coil or continuous conduit, which, in cross section, is of annular form instead of tubular form, thereby providing a passageway for the oil which is of such dimensions

the oil and heat the oil uniformly. The coil or conduit is preferably provided with a center space arranged inside of said annular oil passageway, which space is sealed at 60 one end and provided at its opposite end with a pressure gage. If desired, said annular oil passageway may be provided with one or more spiral vanes so as to cause the oil to follow a spiral path in flowing 65 through said passageway, thus insuring all portions of the oil coming in direct contact with the walls of said passageway to which the heat is applied.

Figure 1 of the drawings is a vertical sectional view of an oil still or oil treating apparatus constructed in accordance with my invention; and

Fig. 2 is a perspective view of a portion of the coil or continuous conduit of said 75 apparatus through which the oil being heated or treated flows.

Referring to the drawings which illustrate one form of my invention, A designates a tubular structure of coil form or 80 other desired shape through which oil that is to be distilled or treated flows, and B designates burner ports or other suitable means for heating said tubular structure. In the form of my invention herein shown 85 the member A consists of a coil formed from two pipes or tubes 1 and 2 arranged one within the other and spaced apart so as to form an annular passageway x through which the oil being heated or treated flows. 90 One end of the annular passageway x communicates with a supply pipe 3 through which the oil is supplied to same, and the opposite end of said passageway communicates with a discharge pipe 4. The center 95 space y inside of the pipe 2 is sealed or cut off from the atmosphere at one end by means of a valve 2^a that is normally closed and a pressure gage 5 is arranged at the opposite end of said space. Any suitable means can 100 be used for holding the pipe 2 centered with relation to the pipe 1, but I prefer to arrange one or more spiral vanes 6 between said pipes, as shown in Fig. 2. The vanes 105 6 hold the pipes 1 and 2 in proper spaced relation and they also cause the oil flowing through the passageway x to be agitated and thoroughly mixed and come in contact with the outer wall of said passageway to which the heat is applied.

An oil heating means of the construction above described is more efficient than a coil

or continuous conduit formed from ordinary pipe or tubing, owing to the fact that the oil passageway of same is of such form that a relatively shallow body of oil flows 5 in contact with a surface of relatively great area to which heat is applied, the depth of the body of oil flowing through said passageway being small enough so that the heat can readily penetrate through the oil and 10 heat all portions of same uniformly. The fact that it is not necessary to use an extremely high temperature, so as to insure the heat penetrating through the oil, as is necessary in oil stills and oil treating apparatus of the kind now in general use, 15 eliminates the possibility of the oil becoming scorched; and still another desirable feature of such a device is that the spiral vanes that are arranged in the annular oil passageway cause the oil to be thoroughly mixed and brought in direct contact with a portion of the passageway to which the heat is applied while it is flowing through 20 said passageway.

25 As previously stated, the center space y that is surrounded by the annular oil passageway x is sealed at one end and provided at its opposite end with a pressure gage. By constructing the device in this manner 30 I produce a pyrometer that shows the average temperature of the entire body of oil flowing through the device, for when the still or apparatus is in operation the air or gases in the center space y expand as the 35 temperature of the oil is raised, and thus operate the pressure gage. In other words, when the still or apparatus is in operation, the pressure in the sealed center space y increases or decreases in direct proportion 40 to the increase or decrease in temperature of the oil flowing through the annular passageway x surrounding said space, thereby enabling the operator in charge of the apparatus to ascertain the average temperature 45 of the entire body of oil flowing through the member A by simply observing the pressure gage 5. With an ordinary heating coil or continuous conduit it is possible to get the temperature of the oil flowing through 50 same only at the point where the bulb of

the thermometer or of the thermo-couple of the pyrometer is introduced into the coil. My improved device is so constructed, however, that it shows at all times the average temperature of the entire body of oil flowing through the oil passageway x .

Having thus described my invention, what I claim, and desire to secure by Letters Patent, is:

1. An apparatus of the character described provided with a passageway of annular form in cross section through which oil flows and also a closed space in which a variable pressure is created according to the temperature of the oil flowing through said passageway, means for heating said passageway, and means for indicating the pressure in said closed space.

2. An apparatus of the character described, provided with a continuous conduit whose interior is divided into an annular passageway through which oil flows and a center space surrounded by said passageway, said center space being cut off from the atmosphere so as to cause the air or gases in said space to vary in pressure as the temperature of the oil flowing through said passageway varies, and means combined with said center space for indicating the average temperature of the oil flowing through said passageway.

3. An oil heating device for the purpose described, comprising a continuous conduit formed from two pipes or tubular members arranged one within the other, spiral vanes arranged between said pipes, the inner pipe being sealed to the atmosphere, and means for indicating the pressure in said inner pipe.

4. An apparatus of the character described, provided with a double walled coil arranged so that the center portion of same forms a closed pressure chamber that is surrounded by a passageway through which oil circulates, means for indicating the pressure in said pressure chamber, and means for applying a heating medium to the exterior of said coil.

CHARLES F. GAISER.
